WASH FOUNTAIN

Howard A. Mullett, Milwaukee, Wis., assignor to
 Bradley Washfountain Company, Milwaukee,
 Wis., a corporation of Wisconsin

Application April 1, 1935, Serial No. 14,076

8 Claims. (Cl. 4—166)

The invention relates to washfountains and more particularly to the basin structure for such fountains.

The principal object of the invention is to provide a basin structure in which the bowl is made as a sheet metal stamping of substantially uniform thickness either of non-corrodible or rust resisting metal or of enamelled metal and of relatively light weight by the use of a relatively light gauge metal and the reinforcement thereof by a metal plate which is secured to the bowl and connected to the supporting pedestal.

Another object of the invention is to provide a washfountain in which the bowl or basin may be readily attached to its support.

The invention further consists in the several features hereinafter set forth and more particularly defined by claims at the conclusion hereof.

In the drawing:

Fig. 1 is a vertical sectional view taken on the broken line 1—1 of Fig. 2;

Fig. 2 is a detail plan view of a structure embodying the invention, parts being broken away;

Fig. 3 is an enlarged sectional view of parts shown in Fig. 1;

Fig. 4 is a detail sectional view taken on the line 4—4 of Fig. 3.

Referring to the drawing, the numeral 6 designates the basin or bowl, 7 the supporting pedestal and 8 a reinforcing plate between said bowl and pedestal and respectively secured thereto.

The bowl 6 is formed as a sheet metal stamping having a conically inclined bottom portion 9, sides 10, and a turned over edge 11, there being a centrally disposed opening 12 for the water and drain fixtures. The metal may be rust resisting metal, such as stainless steel, or it may be sheet steel treated as by the usual enamelling process to have a protective coating. The stamping is of substantially uniform thickness so that it may be readily enamelled and owing to the use of the reinforcement hereinafter described is of relatively light gauge metal so that the basin structure is relatively light, thus reducing the cost of manufacture and facilitating its shipping and installation.

The pedestal 7 has a flanged base portion 13 and a cylindrical body portion 14.

The plate 8 is of conically inclined annular form adapted to abut against a portion of the bottom portion 9 of the basin and project on opposite sides of the siding or body portion 14 of the pedestal and sufficiently beyond the outer side thereof as to reinforce the bowl 6 against

bending strains. This plate permits making of the bowl 6 itself of a lighter weight gauge than could be satisfactorily employed provided the bowl is set directly upon the pedestal of the diameter used.

The plate 8 is secured as hereinafter described to the basin prior to shipping and these assembled parts are secured to the pedestal as hereinafter described when the fountain is installed at the place of use.

As here shown, the plate is secured to the pedestal by providing a plurality of radially disposed studs 15 having threaded engagement with the sleeves 16 whose heads 16' are spot welded to the plate, said studs extending through holes 17' 15 in similarly disposed brackets 17 spot-welded to the inner side of the body portion 14 of the pedestal, clamping nuts 18 and washers 19 being mounted on said bolts.

The plate 8 is detachably secured to the bottom portion of the basin 6 by radially disposed clamping means. Each of these clamps includes a screw bolt 20 connected to the basin through threaded connection with a nut 21 having a flanged head 21' spot-welded to the basin and connected to the plate through a plain washer 22 and a flanged washer 23, the shank of said bolt passing through the openings in said washer and its head engaging the washer 22 and through it exerting a clamping pressure on the flanged washer 23. As the metal basin when formed of ordinary sheet steel has an enamelled surface finish and the plate 8 has a smooth metal finish, a cement is preferably used between these surfaces, more particularly as a filler to compensate for the irregularities of the surfaces of the bowls.

With the above construction, the plate 8 is secured prior to shipping to the basin by bolts 20, nuts 21, washers 22 and 23, and then on installation the basin is mounted on and clamped to the pedestal by the studs 15. The plate 8 makes it possible to use a relatively light gauge metal for the bowl with a vitreous enamel finish and distribute what otherwise would be a concentrated load from the upper edge of the pedestal on the basin over a considerable area of the basin, and thus the structure is free from severe strains and stresses that might cause the enamel on the bottom of the bowl to craze and eventually chip off; and in this connection it is to be noted that basins of this type are sometimes subjected to very heavy cantilever loads, as by users actually sitting on the rims of the bowls, so that the structure has to be sufficiently strong to withstand relatively heavy forces.

I desire it to be understood that this invention is not to be limited to any particular form or arrangement of parts except in so far as such limitations are included in the claims.

5 5. What I claim as my invention is:

1. In a device of the character described, the combination of a sheet metal basin, a support, an annular sheet metal plate secured to said support so as to project beyond the same, and means 10 for clamping said plate against the bottom portion of the basin.
2. In a device of the character described, the combination of a cylindrical sheet metal basin, a tubular support, an annular reinforcing plate 15 abutting the bottom portion of said basin and resting on the top of said support, means securing said plate to said basin, and means for clamping said plate against the top of said support.
3. In a device of the character described, the 20 combination of a cylindrical sheet metal basin having nuts secured to the bottom surface thereof, an annular reinforcing sheet metal plate abutting the bottom portion of said basin, bolts engaging said nuts, washers disposed between 25 said engaging bolts and said plate, a tubular support, said reinforcing sheet metal plate resting on the top of said support, and means for clamping said plate to said support.
4. In a device of the character described, the 30 combination of a cylindrical basin having nuts secured to the bottom face thereof, an annular reinforcing plate abutting the bottom portion of said basin, bolts engaging said nuts, clamping washers engaging said reinforcing plate and secured thereto by said bolts, a tubular support, 35 brackets on said support, and clamping bolts including nuts secured to said reinforcing plate and studs mounted in said nuts and detachably connected with said brackets.
- 40 5. In a device of the character described, the

combination of a basin of sheet metal having an enamelled outer surface, a support, and an annular metal plate securing said basin to said support and projecting beyond said support to reinforce said basin, and a filler between said 5 basin and said plate.

6. In a device of the character described, the combination of a cylindrical sheet metal basin, a tubular support, an annular reinforcing sheet metal plate abutting the bottom portion of said 10 basin at a distance from the center thereof and resting on the top of said support, means adjacent the outer edge of said plate for securing said plate to said basin, and means adjacent the inner edge of said plate for clamping said plate 15 against the top of said support.

7. In a device of the character described, the combination of a basin of sheet metal having a clamping member secured to the bottom face 20 thereof, an annular sheet metal plate abutting said bottom surface, fastening means connected with said member to clamp said plate to said basin, a tubular support, brackets secured to the inner wall of said support, and fastening means connecting said brackets with said plate to clamp 25 the same against the top of said support.

8. In a device of the character described, the combination of a basin of sheet metal, nuts, each 30 having a flanged base a portion of which is integrally connected with the bottom surface of said basin, an annular sheet metal plate abutting said bottom surface, fastening means connected with said member to clamp said plate to said basin, nuts, each having a flanged base a portion 35 of which is integrally connected with the bottom surface of said plate, a pedestal, and means connecting said plate to said pedestal including fastening means engaging said last named nuts.
